Primary Examiner — Kimberly Barnes(74) *Attorney, Agent, or Firm* — SCHWABE,
WILLIAMSON & WYATT, P.C.(57) **CLAIM**

We claim the ornamental design for a hard hat light assembly, as shown and described.

DESCRIPTION

FIG. 1 is an exploded bottom perspective view of a hard hat light assembly showing our new design to which it may be mounted in a hard hat;

FIG. 2 is a first top perspective view of the hard hat light assembly;

FIG. 3 is a second top perspective view thereof;

FIG. 4 is a top view thereof;

FIG. 5 is a bottom view thereof;

FIG. 6 is a front view thereof;

FIG. 7 is a rear view thereof;

FIG. 8 is a right side view thereof; and,

FIG. 9 is a left side view thereof.

The broken lines are provided for environmental purposes only and form no part of the claimed design.
